UNITED STATES PATENT OFFICE.

AUGUST BESSLER, OF ESSEN, GERMANY, ASSIGNOR TO FRIED. KRUPP AKTIENGESELLSCHAFT, OF ESSEN-ON-THE-RUHR, GERMANY.

LOCKING DEVICE FOR THE DRIVE OF MACHINES WITH PRINTING OR FEELING MECHANISMS.

Application filed July 17, 1924, Serial No. 726,643, and in Germany August 1, 1923.

This invention relates to the drive of machines of the kind which comprise printing mechanisms for printing introduced labels or feeling mechanisms for feeling punched cards and which are adapted to be operated by depressing a releasing key or adjusting a lever.

In order to prevent the operation of the machine from taking place before a label 10 to be printed or a card to be perforated has been introduced, there is provided in connection with the releasing key a feeling stamp which feels the guide of the label and thereby controls the release of the machine-drive.

15 The drawing illustrates as an embodiment of the subject-matter of the invention its application to a cash register.

In the drawing:

20 Fig. 1 is a side elevation of the device, Fig. 2 is an elevation of a part of Fig. 1, showing some elements in a different position;

Fig. 3 is a plan view corresponding to Fig. 1;

25 Figs. 4 to 7 are views of details.

The release of the operation of the cash register is effected by means of keys a^1 . The locking device of the operating shaft itself is not shown because it does not form part 30 of this invention. Pins a^2 of the keys act on a strap a^3 of a rocking member a^5 which is mounted for swinging movement at a^4 and which has a spring a^7 attached to its arm a^6 .

35 A connecting rod a^8 which is pivoted to the arm a^6 has a bent-off portion a^9 which serves as a stop. The left-hand end of the connecting rod is pivoted to an angle lever a^{10} , a^{11} which is freely rotatable on a shaft b^1 . The arm a^{11} of the same has a bent-off portion a^{12} which serves as a stop. A double-armed lever b^2 , b^3 which is fixed 40 to the shaft b^1 is connected with the angle lever a^{10} , a^{11} by means of a torsional spring b^4 (Fig. 3) in such a manner as to cause a pin b^5 of the lever arm b^3 to act on the stop a^{12} of the angle lever. The right-hand end b^6 of the lever arm b^3 is bent off and adapted to cooperate with the stop a^9 of the connecting rod a^8 .

45 Arranged underneath the lever arm b^2 is a roller c^1 (Fig. 3) which is carried by a toothed wheel c^2 and executes a circular movement along with the toothed wheel during each operation of the machine. The lever arm b^3 is provided with a stop a^9 and the arm a^{10} of the angle lever a^{10} , a^{11} is provided with a stop a^{12} .

55 a tongue b^{11} (Figs. 1 and 2) which cooperates with a pin a^{13} of the connecting rod a^8 . An arm b^7 which is likewise rigidly fastened to the shaft b^1 has pivoted to it a feeling stamp b^8 (see also Figs. 4 and 5) possessing a slot which is engaged by a stationary guide pin d^1 . Arranged below the feeler is the stationary label guide d^2 the plate d^3 of which supports the introduced label Z . The plate d^3 is provided with a recess d^4 through which the toe b^9 of the feeling stamp b^8 can be passed if the recess d^4 is not covered by an introduced label. Arranged below the label guide d^2 is the set of types e and above the guide the printing punch f^1 . The printing punch has its movements imparted to it by means of a double-armed lever f^2 which is mounted for rocking motion on a stationary shaft d^5 and the arm f^3 of which is pivoted to the rod f^4 which is connected with the driving mechanism of the machine. A pin f^5 of the printing punch f^1 is in engagement with a guide fork g^1 the slotted arm g^2 of which is engaged by a pin g^3 of a setting member g^4 (see also Figs. 6 and 7) which determines the position of the guide fork and consequently the direction of movement of the printing punch f^1 . Fig. 1 shows the guide fork g^1 in the normal position in which the printing punch f^1 may be moved towards the types e and the printing of the introduced label Z effected. The setting member g^4 is rotatable with the key pin g^5 and adapted to be reversed by 180 degrees in the direction of the arrow p^1 by means of a key so as to render inoperative the movement of the printing punch f^1 . The setting member g^4 is held in one or the other of its limit positions by a spring g^6 . Fastened to the setting member is a locking pin g^7 which, upon the setting member being reversed, comes into the path of a stop member b^{10} of the arm b^7 (Fig. 2). The guide fork g^1 has connected to it a locking strap g^8 which obstructs the label guide in the reversed position of the setting member g^4 .

50 100 105 The operation of the device is as follows: If labels should be printed upon the transaction effected by the cash register, the setting member g^4 must be in the position according to Fig. 1. Upon depressing one of the keys a^1 the connecting rod a^8 with the stop a^9 and the arm a^{10} of the angle lever a^{10} , a^{11} is provided with a stop a^{12} .

- lever a^{10} , a^{11} are moved forwards contrary to the action of the spring a^7 , while the arm a^{11} of the angle lever is swung upwards. The pin b^5 bears against the stop a^{12} under 5 the action of the torsional spring b^4 and the double-armed lever b^2 , b^3 follows the movement of the angle lever a^{10} , a^{11} until the parts b^1 to b^{11} are arrested by the feeler b^8 striking on the introduced label. The arrangement 10 is so that, when the said parts are being arrested, the locking member b^6 (position b^{61}) is not yet in the path of the stop a^9 , thereby allowing the parts a^1 to a^{12} to be moved into their limit position. The fully depressed key a^1 causes now the release 15 of the cash register operation by which the printing punch f^1 is moved against the set of types e and the introduced label Z printed.
- 20 If in the position of the setting member according to Fig. 1 no label has been introduced by mistake, the feeler b^8 will not be stopped upon depressing one of the keys a^1 but it will continue its movement through 25 the recess d^1 . The locking member b^6 moved along with the feeler b^8 will now enter into the path of the stop a^9 (position b^{92}) before the parts a^1 to a^{12} will have been moved into the limit position. Therefore it is not possible 30 to fully depress the key a^1 and the operation of the cash register will not be released.
- In order to allow operations of the cash register to take place without having to introduce a label to be printed, it is necessary 35 to turn the key pin g^5 for 180 degrees in the direction of the arrow p^1 by means of a key. The locking pin g^7 is thereby brought into the path of the stop member b^{10} (Fig. 40 2). When a key a^1 is now depressed, the parts b^1 to b^{11} will be arrested by the stop member b^{10} striking against the locking pin g^7 before the locking member b^6 (intermediate position b^{61}) will have been able 45 to come into the path of the stop a^9 . Therefore the key a^1 may again be fully depressed and an operation of the cash register take place without a label having been introduced. By reversing the setting member g^4 50 the guide fork g^1 has also been brought into another position. The printing punch f^1 is thereby prevented from coming into touch with the coloured types e in operations of the cash register without an introduced label.
- 55 Besides, by the reversing of the setting member g^4 the label guide d^2 has been obstructed inasmuch as the right-hand end of the locking strap g^8 has been caused to bear on the plate d^3 of the label guide. It is therefore 60 impossible to insert a label when operations of the cash register take place with which the movements of the printing punch f^1 are inoperative.
- If operations of the cash register should 65 again take place in which labels are to be

printed, this is only possible after the printing punch f^1 has been returned into operative position by a rotation of the key pin g^5 in a direction opposite to the arrow p^1 .

After the depressed key has been released 70 in well-known manner during the operation of the cash register and rushed back, the parts a^2 to a^{12} and along with them the parts b^1 to b^{11} are returned by the action of the spring a^7 . This return movement is 75 assisted in and secured by the roller c^1 which returns the parts b^1 to b^{11} into the position of rest by acting on the arm b^2 before the revolution of the wheel c^2 comes to an end. During this movement the tongue b^{11} acts 80 on the pin a^{13} of the connecting rod a^8 and thus secures also a positive return of the parts a^1 to a^{12} .

I claim:

1. In a machine of the character stated, 85 drive means, releasing means for said drive means, and a feeler operable on a card introduced into said machine for controlling the operation of said releasing means, said feeler being under the influence of said releasing means.

2. In a machine of the character stated, 90 drive means, a key for releasing said drive means, and a feeler operable on a card introduced into said machine for controlling the operation of said key, said feeler being under the influence of said key.

95 3. In a machine of the character stated, drive means, means for releasing said drive means, a spring actuated follower controlled by said releasing means, a feeler positively connected to said follower and displaceable thereby toward a card introduced into said machine, and a stop for said releasing means on said follower movable into stopping position except when said feeler is checked by a card introduced into said machine.

100 4. In a machine of the character stated, drive means, means for releasing said drive means, a card guide, a feeler operable on a card introduced in said guide upon an actuation of said releasing means, and means controlled by said feeler for locking said releasing means on the absence of a card in said guide.

110 5. In a machine of the character stated, drive means, means for releasing said drive means, a card guide, a feeler adapted to be arrested by a card introduced in said guide, said feeler being impositively controlled from said releasing means, and locking means controlled by said feeler adapted to prevent an operative actuation of said releasing means on the absence of a card in said guide, said releasing means being operatively actuatable independently of said feeler upon the arrest of the latter.

115 6. In a machine of the character stated, drive means, means for releasing said drive means, a card guide, a feeler operable on

- a card introduced in said guide, an impulsive connection between said releasing means and said feeler, means controlled by said feeler for locking said releasing means 5 to prevent an operative actuation of the latter on the absence of a card in said guide, and means for rendering said connection inoperative for preventing the locking of said releasing means upon the actuation of 10 the latter subsequent to the introduction of a card in said guide.
7. In a machine of the character stated, drive means, a key for releasing said drive means, a rocking lever, spring means for 15 rocking said lever under the control of said key, a feeler under the positive influence of said lever and operable on a card introduced into said machine, said lever having a lug adapted to prevent a full depression 20 of said key on the absence of a card in said machine.
8. In a machine of the character stated, drive means, a key for releasing said drive means, means for marking a card introduced 25 into said machine, a feeler for controlling the operation of said key in dependence upon the presence or absence in said machine of a card to be marked, and settable means for rendering said key independent of said feeler.
9. In a machine of the character stated, drive means, a key for releasing said drive means, means for marking a card introduced into said machine, a feeler for controlling 35 the operation of said key in dependence upon the presence or absence in said machine of a card to be marked, and settable means adapted to control said feeler for rendering said key independent 40 thereof.
10. In a machine of the character stated, drive means, a key for releasing said drive means, a card guide, a feeler operable on a card introduced into said guide and controlling in dependence thereupon the operative actuation of said key, and a setting member operable for freeing said key from the control of said feeler, said member having a projection thereon adapted to obstruct said card guide when said member is in 45 operative position.
11. In a machine of the character stated, drive means, a key for releasing said drive means, a card guide, a feeler operable on a card introduced into said guide and controlling in dependence thereupon the operative actuation of said key, a setting member operable for freeing said key from the control of said feeler, printing means operable on said card upon an operative actuation 55 of said key, and means whereby said printing means is rendered inoperative when said member is in operative position.
12. In a machine of the character stated, drive means, a key for releasing said drive means, a card guide, a feeler operable on a card introduced into said guide and controlling in dependence thereupon the operative actuation of said key, a setting member operable for freeing said key from the 60 control of said feeler, printing means operable on said card upon an operative actuation of said key, and means whereby said printing means is swung into inoperative position when said member is set in operative position.

The foregoing specification signed at Cologne, Germany, this 5th day of July, 1924.

AUGUST BESSLER.
